Primary Examiner—Ralf Seifert

[57] CLAIM

The ornamental design for a zipper puller, as shown and described.

DESCRIPTION

FIG. 1 is a front elevational view of the zipper puller of the present invention;

FIG. 2 is a top plan view of the zipper puller of FIG. 1;

FIG. 3 is a right side elevational view of the zipper puller of

FIG. 1, the left side elevational view being a mirror image

thereof; and,

FIG. 4 is a rear elevational view of the zipper puller of FIG.
